UNITED STATES PATENT OFFICE

PERCY E. HUNTER AND LOUIS E. ENDSLEY, OF PITTSBURGH, PENNSYLVANIA; SAID
ENDSLEY ASSIGNOR TO SAID HUNTER

METHOD OF AND APPARATUS FOR SEPARATING METAL SHEETS

Application filed June 17, 1929. Serial No. 371,327.

Our invention relates to a method of an apparatus for loosening or separating the metal sheets of a pack, such as the sheets contained in the piles or stacks of steel sheets in connection with tin plate mill operations, etc.

In tin plate mill operations, the metal sheets are handled in piles or packs, during annealing and other operations, and frequently the sheets of a pack become stuck together so that separation thereof in a convenient manner without injury to the sheets presents a troublesome problem.

One object of our invention is to provide a means and a method by which the sheets of a pack can be rapidly and economically separated or loosened from one another, without pounding or bending operations of such nature as will deform or distort the sheets.

One form of apparatus by which our invention may be practised is shown in the accompanying drawing wherein Figure 1 is a side elevational view of a machine for operating upon metal packs, and Fig. 2 is a cross sectional view thereof taken at right angles to the view of Fig. 1.

The apparatus comprises a base or foundation plate 3 that supports a framework 4 which carries the operating parts of the apparatus. A shaft 5 mounted upon the base is driven through a pulley 6 from any suitable source of power and carries worms 7 that mesh with worm gears which are secured to the lower end of shaft 8. These shafts are journaled at their lower ends in the framework 4 and at their upper ends are slidably supported in lateral extensions of a slide 9 whose vertical movements are guided by slideways 10 that are formed in the framework.

Conical rollers 11 have their shafts supported in bearings on the framework 4 and are driven from the shafts 8 through bevel gearing 12. Co-acting conical rollers 13 have their shafts journaled in the slide 9 and are driven from the shafts 8 by bevel gears 14 and 15, the gears 14 having sliding key connection with the shafts 8 and being journaled in the slide 9 so that when the slide 9 is moved vertically, the gear wheels 14 may

travel therewith, and driving connection therefore maintained between the gear wheels 14 and 15.

In order to permit insertion and removal of sheet metal packs between the rollers 11 and 13, and to accommodate the machine to packs of varying thickness, I provide means for raising and lowering the slide 9, such means consisting of a pair of screws 17 that have threaded connection with extensions 18 of the slide 9, and which are journaled in a top plate or bearing plate 19. The upper ends of the screws 17 carry beveled gear wheels 21 that mesh with gear wheels or pinions 22 which are secured to a shaft 23. This shaft is supported in bearings that are mounted upon the plate 19, and is driven by means of a pulley or hand wheel 24 in any convenient manner.

The top plate 19 is connected to the framework 4 at each corner, by means of bolts 25 that are vertically slidable in the framework and which carry springs 26 interposed between the nuts of the bolt and an offset portion of the framework, so that upward thrust upon the plate 19 when the screws 17 are operated to force the rollers 13 into engagement with a pack will be cushioned, thus avoiding excessive strain on the apparatus.

Disposed in a plane transverse to the plane of the slide 9, I mount an idling roller slide 28 that is of generally U form, as shown more clearly in Fig. 2, and which carries a shaft 29 at its lower end upon which deflecting rollers 31 are mounted. The legs of the slide 28 partially embrace and are guided by the slide 9, slideways 32 being provided in the slide 9 for guiding the slide 28 in its vertical movements. A cross head 33 is secured to the upper ends of the legs of the slide 28 and have threaded connection with screw shafts 34 which are journaled in the top plate 19 and in a bearing plate 35 which is mounted on said top plate. The screws 34 have bevel gear connection with a shaft 36 that is mounted in bearings formed on the plate 35 which is driven by a pulley or hand wheel 37.

In operation, the slides carrying the rollers 13 and 31 are elevated to permit insertion of a metal pack 39 whose sheets it is

desired to loosen or separate, the center of the pack preferably coinciding with the vertical center line of the machine. The screws 17 will then be actuated to move the rollers 13 into driving engagement with the pack.

5 It will be seen that the rollers 13 and 11 have their axes so inclined that the surfaces thereof which engage the upper and lower sides of the pack will lie in horizontal lines.

10 The tapering of the rolls effects rotation of the pack upon movement of the shafts 8 in a circular path, without slippage of any portion of the roll surfaces upon the pack.

While the rollers 13 have been moved down 15 in position to rotate the pack, the shaft 36 is operated to move the slide 28 and its rollers 31 downwardly to somewhat the position shown in Fig. 2, thus deflecting those portions of the pack to either side of the axes of the rollers 11-13. The rotation of the 20 pack by the rolls 11 and 13 will result in the bending thereof by the rolls 31, the portions thus deflected being brought again to a horizontal plane by the rollers 11 and 13. During 25 the rotation of the pack, the rolls 31 may be gradually moved downwardly to effect gradual deflection of a pack to a desired degree. These rolls may be driven if desired, instead of having merely idling movement.

30 The rollers 31, while of generally tapered form have their surfaces somewhat concave in a direction longitudinally of their axes, so that the pack will have effective continuous contact therewith from the outer edge of the 35 pack to the inner ends of the rolls and slippage of the pack with respect to the rolls thereby avoided.

The continued deflection of the sheets by the rollers 31 and return of the deflected portions to a horizontal plane between the rollers 11-13, results in effectively loosening the sheets from one another, and after a pack has been subjected to the operation above described, the slide 9 and 28 will be elevated to 45 permit removal of the pack and insertion of another pack.

We claim as our invention:—

1. The method of operating upon packs composed of sheets of material, which comprises rotating a pack about an axis perpendicular to the plane of the pack and simultaneously deflecting portions of said pack into undulatory paths of travel.

2. The method of operating upon packs composed of sheets of material which comprises rotating a pack about an axis perpendicular to the plane of the pack and simultaneously deflecting portions of said pack in a direction perpendicular to said plane along one diametral line of the rotative path and causing the deflected portions of the pack to return to the original plane thereof at another diametrical line of said path.

3. The method of operating upon packs composed of sheets of material, which comprises rotating a pack about an axis perpendicular to the plane of the pack by forces applied to the top and bottom sheets thereof, deflecting portions of said pack into undulatory paths of travel and imparting a squeezing action to said pack following deflections thereof.

4. Apparatus for operating upon packs of sheet material, comprising rollers of tapered form for imparting rotative movement to a pack and a roller of generally tapered form offset from the normal plane of the pack, for deflecting portions of said pack during rotative movement thereof, the first-named rollers being adapted to contact with the pack along lines extending from the edges of the pack to approximately the mid point thereof.

5. Apparatus for operating upon packs of sheet material, comprising rollers of tapered form for imparting rotative movement to a pack, a roller of generally tapered form offset from the normal plane of the pack for deflecting portions of said pack during rotative movement thereof, and means for adjusting said deflecting roller in a direction transversely of the said plane, all of said rollers being adapted to contact with the pack along lines extending from the edges of the pack to approximately the mid point thereof.

6. Apparatus for operating upon packs of sheet material comprising two pairs of tapering rollers, the reduced ends of one pair of rollers being disposed in proximity to the reduced ends of the other rollers, means for driving said rollers to effect rotative movement of a pack of material placed between the rollers of each pair about an axial line extending through the pack at a point adjacent to the inner ends of the rollers, and deflecting members disposed on a line substantially at right angles to the axes of the first-named rollers, the said member being offset from the normal plane of a pack disposed between said feed rollers, to effect deflections of said pack during rotative movement thereof.

7. The method of operating upon a pack of sheets, which comprises rotating said pack about an axis perpendicular to the plane of the pack, pressing the sheets together at one point in their path of rotative movement, while rotating, and deflecting portions of said pack at another point in said path, in a direction transversely of the plane which portions of the pack assume when being pressed.

8. Apparatus for operating upon packs of sheet material, comprising driving rollers for rotating a pack in a direction generally parallel to the plane thereof, and about an axis perpendicular to and adjacent to the
